UNITED STATES PATENT OFFICE.

ALBERT T. BISHOP, OF SOUTHBURY, CONNECTICUT.

LANTERN.

SPECIFICATION forming part of Letters Patent No. 705,816, dated July 29, 1902.

Application filed March 24, 1902. Serial No. 99,775. (No model.)

To all whom it may concern:

Be it known that I, ALBERT T. BISHOP, of Southbury, in the county of Hartford and State of Connecticut, have invented a new and useful Improvement in Lanterns; and I do hereby declare the following, when taken in connection with the accompanying drawings and the figures of reference marked thereon, to be a full, clear, and exact description of the same, and which said drawings constitute part of this specification, and represent, in—

Figure 1, a side view, partially in section, of a lantern constructed in accordance with my invention; Fig. 2, a sectional view on the line *a b* of Fig. 1; Fig. 3, a vertical sectional view through a portion of one side tube, showing the lower end of the sleeve thereon and a spring in the tube for locking the parts together, enlarged; Fig. 4, a side view of a portion of one of the tubes, showing the bail-ear thereon, together with one end of the bail connected therewith; Fig. 5, a side view showing the application of my invention to a cold-blast lantern.

This invention relates to an improvement in lanterns, and particularly to tubular lanterns, and is equally applicable to lanterns in which the air supplied to the burner is admitted through a central tube arranged above the globe or to the well-known type of cold-blast lanterns; and the invention more especially relates to lanterns in which the globe is swung to one side for access to or removal of the burner. In the usual construction of this class of lanterns preparatory to swinging the globe to one side it is necessary to raise it, so that the lower end will clear the top of the burner-cone, and before the globe is raised it is necessary to lift the bell or hood, and this is usually done by independent means.

The object of this invention is to arrange a sleeve upon one of the side tubes and connect the bell or hood with its upper end and also connect the globe-holder with the tube, so that by one operation both members may be raised and when raised the globe may be swung to one side.

Another object of the invention is to lock the globe-holder in its normal position and to provide means for holding it in its elevated position; and the invention consists in the details of construction and combinations of

parts, as will be hereinafter described, and particularly recited in the claims.

The base or font 2, side tubes 3 4, and central tube 5, which connects with the side tubes at the top of the lantern, may be of usual construction, as is also the burner 6, globe-rest 7, and globe-guard 8. Upon the side tube 4 is a sleeve 9, to the lower end of which the globe-rest 7 is rigidly connected by a wire arm 10. To the upper end of the sleeve 9 the bell or hood 11, which is adapted to slide vertically on the central tube 5, is connected by a wire arm 12. This arm encircles the side tube 4 and is connected with the sleeve 9 by having the upper edge of the sleeve turn over the wire, a portion of the sleeve being cut away to form a clearance-slot 13, the purpose of which will hereinafter appear. Also secured to the sleeve 9 is a spring-stay 14, which encircles the top of the globe 15, so as to assist in holding it in position. Within the tube 4 is a spring-catch 16, the tongue 17 of which projects outwardly through a slot 18 in the tube 4 and the slot 19 in the sleeve 9. To raise and swing the globe, the tongue 17 will be pressed inward, so that the sleeve 9 may be raised, the upward movement of which will lift the hood 11, and at the same time raise the globe 15 until its rest 7 clears the burner-cone 6. By this time the lower end of the sleeve 9, within which the arm 10 is secured, will have passed above the upper corner of the tongue 17 and the rest to a position to clear the burner-cone, so that the globe may be swung to one side in the usual manner, the lower end of the sleeve riding upon the upper edge of the tongue 17 and the slot 13 in the upper end of the sleeve permitting it to ride over the wire arm 12. The globe therefore will be held in its lifted position as long as it is turned out of line with the burner. When the globe is swung into line, it will fall by gravity, the weight of the globe drawing the sleeve downward, and hence bringing with it the hood 11. When in their normal positions, the slots 18 and 19 will register, so that the tongue 17, extending through them, will lock the sleeve 10 with the tube. On the upper side of the tubes 3 4 are bail-ears 20, into which the ends of the bail 21 extend, and the upper edges of these ears are formed with notches 22, into

which the bail will spring when the bail is raised to its vertical position, so that the bail or handle will be held upright when desired; but the notches are so shallow and the bail 5 so flexible that the bail may be readily turned down when desired.

In applying my invention to a cold-blast lantern, as shown in Fig. 5 of the drawings, it is necessary to raise the chimney 23 prior 10 to lifting the globe, as the lower edge of the chimney sets over the top of the globe. I therefore connect the chimney 23 with the upper end of the sleeve 24 by an arm 25, corresponding to the arm 12, by which the 15 hood was connected with the sleeve 9 in the construction heretofore described, and on the sleeve 24 I arrange a collar 26, to which the globe-rest 27 is connected by an arm 28. In this sleeve is a slot 29, through which the 20 tongue 17 of the locking-spring extends. In the lower edge of the collar is a notch 30, and in the upper edge is a notch 31, while on the sleeve 24 are pins or studs 32 33, which coact with the collar, as will hereinafter appear. To swing 25 the lantern, the tongue 17 will be depressed to permit the sleeve 24 to be raised, the upward movement of which will lift the chimney 23 upward away from the globe 15. In the meantime the pins 32 33 will have been 30 lifted until the pin 32 comes in contact with the upper edge of the notch 30. The continued upward movement of the sleeve will raise the globe until the globe-rest clears the top of the burner, when the sleeve may be rotated, which will turn the collar, so as to 35 swing the globe to one side, the globe being held on its rest by usual guards 34. The notch 31 and pin 33 might be omitted, although I preferably employ them to give ri-

gidity to the parts. Like the construction first 40 described, the sleeve will be held in its lifted position, as well as locked in its depressed position, by the tongue 17 of the locking-spring.

I am aware that sleeves have been arranged upon one of the tubes of a tubular lantern, 45 with which sleeve the globe-holder has been connected, so as to be raised thereby, and therefore do not wish to be understood as claiming such as my invention.

Having thus fully described my invention, 50 what I claim as new, and desire to secure by Letters Patent, is—

1. In a tubular lantern, the combination with the side tubes thereof, of a vertically-movable sleeve arranged upon one of said 55 tubes, rigid connection between the sleeve and globe-rest and swivel connection between the sleeve and a portion of the lantern above the globe whereby the upward movement of the sleeve will raise the globe and a 60 portion of the lantern above the same, so as to permit the globe to be swung to one side, substantially as described.

2. In a tubular lantern, the combination with one of the said tubes, hood and globe- 65 rest thereof, of a vertically-movable sleeve arranged on said tube, a swivel connection between the hood and the upper end of the sleeve, and a rigid connection between the globe-rest and lower end of the sleeve, sub- 70 stantially as described.

In testimony whereof I have signed this specification in the presence of two subscribing witnesses.

ALBERT T. BISHOP.
